UNITED STATES PATENT OFFICE.

ROBERT M. PIERSON, OF AKRON, OHIO, ASSIGNOR TO THE B. F. GOODRICH COMPANY, OF NEW YORK, N. Y., A CORPORATION OF NEW YORK.

DESIGN FOR A TANK-BULB.

54,223.

Specification for Design.

Patented Nov. 18, 1919.

Application filed August 13, 1919. Serial No. 317,357. Term of patent 14 years.

To all whom it may concern:

Be it known that I, ROBERT M. PIERSON, a citizen of the United States, residing at Akron, in the county of Summit and State of Ohio, have invented a new, original, and ornamental Design for Tank-Bulbs, of which the following is a specification, reference being had to the accompanying drawings, forming a part thereof, in which—

Figure 1 is a top plan view of a tank bulb bearing my new design.

Fig. 2 is a side elevation thereof.

I claim:

The ornamental design for a tank bulb as shown,

ROBERT M. PIERSON.
